UNITED STATES PATENT OFFICE

PERRY H. HAMILTON, OF BALTIMORE, MARYLAND, ASSIGNOR TO MAINTENANCE EQUIPMENT COMPANY, OF CHICAGO, ILLINOIS, A CORPORATION OF ILLINOIS

WHEEL FLANGE OILER

Application filed October 22, 1928. Serial No. 314,166.

This invention relates to new and useful improvements in wheel flange oilers, and more particularly to improved oil spreading devices for distributing the oil evenly on the wheel flange and railhead.

Numerous devices have been provided for projecting oil from a reservoir mounted adjacent the rail onto the flange of a passing car wheel. In one approved type of oiler, a pumping mechanism having a plunger which is depressed by the wheel flange acts to project oil upwardly from the reservoir onto the wheel flange. An approved example of such an oiler is disclosed in the co-pending application of Hamilton, Serial No. 262,452, filed March 17, 1928. The oil spreading devices forming the particular subject matter of this present invention are designed particularly to cooperate with oil projecting devices of the type disclosed in said co-pending application, although they are adaptable for use with other types of devices for applying the oil to the wheel flange.

The principal object of the invention is to provide a wiping device which yieldably engages the inner surface of the wheel flange so as to spread oil that has been projected onto the flange evenly around the entire periphery of the flange.

Another object is to provide troughs in connection with said wiping devices for catching surplus oil that is wiped from or dropped from the flange, so that this oil may be used again.

Another object is to provide means for retaining oil that finds its way behind the wiping device so that it may be squeezed out into engagement with the wheel flange.

Another object is to provide means for suitably supporting said oil spreading devices adjacent the side of the rail head and between the spaced oil projecting devices.

Other objects and advantages of this invention will be more apparent from the following detailed description of certain approved forms of the apparatus.

In the accompanying drawings:

Fig. 1 is a plan view of a portion of a series of oiling devices, with one approved form of

spreading device interposed between the several oilers.

Fig. 2 is an elevation of the assembly shown in Fig. 1.

Fig. 3 is a transverse vertical section, taken substantially on the line 3—3 of Figs. 1 and 2.

Fig. 4 is a perspective view of one of the spreaders, as used in Figs. 1, 2 and 3.

Fig. 5 is a transverse vertical section showing a modification.

Fig. 6 is a view similar to Figs. 3 and 5 showing another modification.

Fig. 7 is a transverse vertical section showing a worn track rail on a curve, illustrating the principles upon which this present invention is based.

At A, B, and C in Figs. 1 and 2 are indicated three of a series of oil-projecting devices which are positioned at spaced intervals along one side of the track rail 1. Each of these devices, in the example here shown, comprises an oil reservoir 2, provided with a cover plate 3, the assembly being secured at its rear side to the supporting plate or bar 4 which is shaped to fit between the head 5 and base flange 6 of the rail 1, and secured in place by bolts 7, passing through the web of the rail. Within the reservoir is positioned an oil pumping mechanism comprising a plunger 9 which projects up through a suitable opening in the cover plate and is positioned in the path of the wheel flange 10 (see dotted lines, Fig. 3) so that when a wheel passes above the oiling device, the plunger 9 will be depressed and the pumping mechanism will project oil upwardly through a suitable outlet passage, or passages 11 onto the inner surface of the wheel flange 10. In the example here shown, the outlet passages 11 are formed in a flange 12, which projects up alongside the rail head 5 so as to direct the oil properly onto the inner surface of the wheel flange.

It will be apparent that even though a plurality of these oiling devices are used as a series, positioned at spaced intervals along the rail, the oil will be applied to more or less localized portions of the rail flange and will have to be distributed thereon by rubbing against the rail head as the wheel rotates.

It has been found that the inner surface of a rail on a curve will become "curve worn", as indicated at 13 in Fig. 7, and that with the aid of such a worn rail a better distribution of oil is gained, due to the greater area of contact with the side of the wheel flange, as shown in Fig. 7. Where a "full ball" new rail is used, as shown for example in Figs. 3, 5, and 6, there is very little smearing or spreading effect on the wheel flange, due to the small area of side contact between the flange and rail. The purpose of the present invention is to provide an auxiliary means for spreading the oil on the wheel flanges after they have passed over the oiling devices, and for some distance beyond the oiling device.

A simple example of a means for performing this function is shown in Fig. 5. A plate 14 is shaped at 15 and 16 to fit between the base flange and head of the rail, and is secured to the web of the rail by means of bolts 17 or other suitable fastening devices. The plate 14 is provided with a flange 18 which projects up along the inner side of the rail head 5, the surface of flange 18 adjacent the rail flange 10 being beveled, as shown at 19, to correspond to the worn surface 13 of a "curve worn" rail as illustrated in Fig. 7. This inclined surface 19 will engage the greater portion of the inner surface of wheel flange 10 and serve to spread the oil along the flange.

In the modification shown in Fig. 6, a supporting plate 20 is secured by bolt 21 between the rail base and rail head. A pair of yieldable metal strips or plates 22 and 23 are riveted together at 24, and the wider plate 22 is secured to supporting plate 20 by screws or other means, as indicated at 25. The plate 22 is bowed outwardly and then curved inwardly toward the rail head 5 so as to form a wiper plate 26 adapted to engage yieldably against the inner surface of the wheel flange 10. The other plate 23 is curved outwardly beneath the wheel flange so as to form together with plate 22, a trough for holding the surplus oil which is squeezed off or drops from the wheel flange. This oil will be picked up by other portions of the wheel, or other wheel flanges, so as to minimize the waste of oil.

In the form of the invention shown applied in Figs. 1, 2 and 3, and shown detached in perspective in Fig. 4, a metal plate is bent to form a wiper flange 27, which engages yieldably against the inner surface of the car wheel flange 10. This flange 27 will be of sufficient length to extend substantially from the oil outlet flange 12 of one oil projecting device to the corresponding flange 12 of the next adjacent device, all as indicated in Figs. 1 and 2. The lower portion of the flange 27 may rest upon the cover plates 3 of adjacent oilers. The central portion 28

of this spreading means is shorter than the flange 27 and substantially equal in length to the distance between two adjacent reservoirs 2. This portion 28 comprises a downwardly extending flange 29, a horizontal flange 30 and an upwardly extending flange 31, thus forming a trough for catching the oil that drops from the wheel flange. The ends of the horizontal flange 30 may be extended, as indicated at 32, these projections 32 being inserted between the top of reservoir 2 and its cover plate 3, so as to hold the spreading device in place.

An additional spring flange 33 may be attached to the rear of flange 27 and project into engagement with the lower portion of the side of the railhead 5 thus forming a pocket which is closed at the ends by the overlapping end flanges 35 and 36 turned respectively from the flanges 27 and 33. Oil that finds its way behind the flange 27 will be entrapped in the pocket 34, and as the flange 27 is sprung in by the engagement therewith of wheel flange 10 the oil will be squeezed out through the several openings or notches 37 provided in the upper edge of flange 27.

As a further modification, means (such as the plunger-operated feeder device disclosed in Figs. 1 and 2) might be used for forcing oil directly into the pocket 34 behind the spreader flange. This oil would flow out through the notches 37, and would also be squeezed out by the passing car wheel flange as it pressed in the spreader flange 27.

The form of the invention illustrated in Figs. 1 to 4 inclusive is particularly adaptable for use between adjacent units of a series of oilers positioned at spaced intervals along the track. The forms shown in Figs. 5 and 6 may be used either between the oilers, or for any suitable distance beyond these oiling devices.

Preferably the series of oiling devices will be positioned some little distance in advance of a curve or switch point, and a suitable number of these spreading devices will be positioned along the rail beyond the oiling devices to insure a complete spreading of the oil on the wheel flange before the wheel reaches the curve or switch point.

It will be apparent that these oil-spreading devices could be used in combination with any suitable approved form of means for initially projecting the oil into onto the wheel flange or railhead, although the form here shown diagrammatically by way of example, and shown more in detail in my prior pending application hereinabove referred to, has been found to cooperate most satisfactorily with these spreading devices. While certain approved forms of the oil spreading devices have been here shown and described by way of example, it will be apparent that many changes in design and proportions will

be possible without departing from the principles of this invention as set forth in the claims which follow. The wheel-engaging spring flanges of the spreading plates or wipers, as shown in the preferred forms of the invention, insure a substantially constant contact with the inner surface of the wheel flange as the wheel passes thereover, whereby a maximum spreading effect is obtained.

10 I claim:

1. An oil spreader for wheel flange oilers, comprising a plate extending longitudinally of the rail and inclined to substantially fit against the inner surface of the wheel flange, and means for supporting the plate at the side of the railhead.

2. An oil spreader for wheel flange oilers, comprising a yieldable plate extending longitudinally of the rail and inclined to substantially fit against the inner surface of the wheel flange, and means for supporting the plate at the side of the railhead.

3. An oil spreader for wheel flange oilers, comprising a plate formed of spring metal inclined to substantially fit against the inner surface of the wheel flange, and means for supporting the plate at the side of the railhead.

4. An oil spreader for wheel flange oilers, comprising a wiping plate adapted to engage the inner surface of the wheel flange and a trough to catch surplus oil, and means for supporting the plate and trough at the side of the railhead.

5. An oil spreader for wheel flange oilers, comprising a yieldable wiping plate adapted to engage the inner surface of the wheel flange and a trough to catch surplus oil, and means for supporting the plate and trough at the side of the railhead.

6. The combination with a plurality of devices for projecting oil against the car wheel flange, said devices being positioned at spaced intervals along one side of the rail, of oil spreaders adapted to be interposed between the projecting devices, each spreader comprising a wiper plate extending longitudinally of the rail and adapted to engage the inner surface of the car wheel flange.

7. The combination with a plurality of devices for projecting oil against the car wheel flange, said devices being positioned at spaced intervals along one side of the rail, of oil spreaders adapted to be interposed between the projecting devices, each spreader comprising a yieldable wiper plate extending longitudinally of the rail and adapted to engage the inner surface of the car wheel flange.

8. The combination with a plurality of devices for projecting oil against the car wheel flange, said devices being positioned at spaced intervals along one side of the rail, of oil spreaders adapted to be interposed between the projecting devices, each spreader comprising a wiper plate formed of spring metal,

and means for supporting the plates between the projecting devices.

9. The combination with a plurality of devices for projecting oil against the car wheel flange, said devices being positioned at spaced intervals along one side of the rail, of oil spreaders adapted to be interposed between the projecting devices, each spreader being formed of a metal plate bent to form a spring wiper adapted to engage the inner surface of the rail, a trough for catching surplus oil, and means for supporting the spreader between the oil-projecting devices.

10. The combination with a plurality of devices for projecting oil against the car wheel flange, said devices being positioned at spaced intervals along one side of the rail, each oil-projecting device comprising a reservoir and a cover plate therefor, of oil spreaders adapted to be interposed between the several projecting devices, each spreader being formed of a metal plate bent to form a spring wiper adapted to engage the inner surfaces of the rail, a trough for catching surplus oil, and a pair of oppositely projecting flanges each adapted to be interposed between the reservoir and cover plate of the adjacent oil projecting device.

11. An oil spreader for wheel flange oilers, comprising a spring plate inclined to substantially fit against the inner surface of the wheel flange at the side of the railhead, and means behind the plate for retaining oil.

12. An oil spreader for wheel flange oilers, comprising a spring plate inclined to substantially fit against the inner surface of the wheel flange at the side of the railhead, and means behind the plate for retaining oil, there being openings formed in the upper portion of the plate whereby the oil behind the plate may be squeezed out as the plate is sprung inwardly by a wheel flange.

13. In combination with means for projecting oil from a reservoir, an oil spreader comprising a spring plate inclined to substantially fit against the inner surface of the wheel flange at the side of the railhead, and means behind the plate for storing oil provided by the projecting device, this oil being expelled at the upper edge of the plate when the spring plate is forced inwardly by pressure imposed by a passing car wheel flange.

14. In combination with means for projecting oil from a reservoir, an oil spreader comprising a spring plate inclined to substantially fit against the inner surface of the wheel flange at the side of the railhead, and means behind the plate for storing oil provided by the projecting device, there being a plurality of openings formed in the upper portion of the plate through which this oil is expelled as the plate is forced inwardly by pressure imposed by a passing car wheel flange.

15. An oil spreader for wheel flange oilers,

comprising a wiper plate adapted to be mounted at one side of the railhead so as to extend longitudinally of the rail, said plate tapering upwardly and inwardly toward the rail so as to substantially fit between the railhead and inner surface of the wheel flange.

16. An oil spreader for wheel flange oilers, comprising a supporting member mounted at the side of the rail, and a pair of metal plates
10 secured together and to the supporting member, one of the plates being bent upwardly and inwardly to form a yieldable wiper engaging the inner surface of the wheel flange, and the other plate being bent outwardly to
15 form a trough beneath the flange for catching surplus oil.
